CHILDREN'S PLAYGROUND SLIDE OR SIMILAR ARTICLE

William Accorsi, 80 Jefferson St.,
New York, N.Y. 10002

Filed Mar. 24, 1966, Ser. No. 1,624

Term of patent 14 years

(Cl. D34—5)

FIGURE 1 is a top plan view of a children's playground slide or similar article, illustrating my new design;

FIGURE 2 is a side elevation of the children's playground slide or similar article;

FIGURE 3 is a bottom plan view of the children's playground slide or similar article;

FIGURE 4 is a front elevation of the children's playground slide or similar article; and

FIGURE 5 is a rear elevation of the children's playground slide or similar article.

The essential features of my design reside in the full line portions shown.

I claim:

The ornamental design for a children's playground slide or similar article, as shown and described.
